(57) **CLAIM**

The ornamental design for an aerosolization device, as shown and described.

DESCRIPTION

FIG. 1 is a perspective view of an aerosolization device embodying the new design;

FIG. 2 is a side elevational view of the aerosolization device of FIG. 1;

FIG. 3 is a front elevational view of the aerosolization device of FIG. 1;

FIG. 4 is a side elevational view of the aerosolization device of FIG. 1, FIGS. 2 and 4 being 180 degrees of rotation to each other;

FIG. 5 is a back elevational view of the aerosolization device of FIG. 1, FIGS. 3 and 5 being 180 degrees of rotation to each other;

FIG. 6 is a top plan view of the aerosolization device of FIG. 1; and,

FIG. 7 is a bottom plan view of the aerosolization device of FIG. 1.

The broken line showing the portions of an aerosolization device is for the purpose of illustrating environmental structure and forms no part of the claimed design.
